STARTER HAVING MAGNETIC JAW ADVANCE

Arnold Schindel, Fair Lawn, and Samuel Gilbert, Cedar Grove, N.J., assignors to Bendix Aviation Corporation, Utica, N.Y., a corporation of Delaware

Application February 27, 1958, Serial No. 717,871

6 Claims. (Cl. 74—7)

This invention relates to starters having means for advancing the starter jaw into engagement with an engine jaw for the starting of the engine, and more particularly concerns such a starter wherein a drive member has a helical spline which mates with a helical spline on the starter jaw and means are required for exerting a restraint on the starter jaw so that it advances for engagement.

The usual method for providing engagement between a starter jaw helically connected to a drive member uses friction effects produced by friction devices which contact the starter jaw. With current starting requirements which call for cranking speeds up to 8,000 r.p.m., the use of friction means for high speed starter jaw engagement is not always dependable. This lack of reliability is due to limitations in the materials which are used and the loss of friction due to wear of parts of the friction devices which impose the restraining axial force.

An object of the present invention is to provide improved magnetic means arranged to cause the starter jaw advancement.

A further object is to provide such a magnetic jaw advancing arrangement wherein the restraint for advance diminishes as the jaw teeth engage and the completion of engagement is accomplished by the inertial effects of the engine rotor.

Another object is the provision of a specific arrangement of permanent magnets on the drive member and the starter jaw which is easily fabricated and assembled.

Another object is the provision of such magnetic jaw advancing means wherein there is adequate magnetic attraction with variation in the rest position of the starter jaw and the starter jaw is held in retracted position after the starting cycle.

The accomplishment of the above objects, along with the features and advantages of the invention, will be apparent from the following detailed description and the accompanying drawing of an embodiment of the invention in which:

Fig. 1 is a longitudinal cross-sectional view of the jaw advancing section of a starter and shows the starter jaw out of engagement with the engine jaw and magnets between the starter jaw and a stationary support member, and

Fig. 2 is an enlarged transverse cross-sectional view through the axial center of the magnets and shows the relative circumferential positioning of the magnets on the starter jaw and the inner stationary member and the relative facing of the magnets when the starter is at rest.

With reference to Fig. 1, it can be realized that, when starter drive member 11 is caused to rotate by means of a clutch pack, planetary gearing and a turbine (none of which is shown), drive member 11 will tend to rotate tubular starter jaw 13 with it due to the helical spline connection unless a radial restraint or normal force is imposed on the starter jaw. When such restraint is imposed by magnetic means (described below), the starter jaw will advance axially by means of the

2

helical spline 15 on the drive member and the complementary loosely-mated helical spline 17 on the outer surface of the starter jaw. With full advancement, the annular starter jaw 13 will have its ring of saw-shaped teeth 19 fully engaged with complementary teeth 21 on the flange part 23 of the starter jaw 25 and the starter can bring the engine up to starting speed when starting motive power is cut off. The starter jaw 25 has axially-extending splines 27 for connection with an aircraft turbine engine. The means for providing motive power to the above-mentioned starter turbine and hence the drive member 11 can be air or combustion gases. After the starter brings the engine to starting speed and the engine tends to drive the starter, the jaws will be conventionally separated due to the configuration of the axial-extending jaw teeth which have the usual axially-extending and inclined faces. Full axial separation or starter jaw retraction is aided by the magnetic means to be described and permits elimination of a spring which was previously used for this purpose and for the prevention of subsequent ratchetting.

The drive member 11 is rotatably mounted by ball bearing 31 on an annular surface 33 of a stationary support member 35 of the starter. The stationary member 35 has an axial tubular extension 37 from surface 33. Within the cavity of extension 37, a coil spring 39 is positioned and restrains resiliently one flanged end of a shaft 41. The other end of the shaft 41 rotatably carries the engine jaw 25.

This arrangement including spring-biased shaft 41 provides for slight axial play when the starter jaw 13 engages the engine jaw 25. It is to be noted that the starter jaw 13 has a radially-extending flange 49 at its inner end which is arranged to limit the axial movement of the starter jaw 13 by abutment with the helical spline of the axially-stationary drive member 11.

With reference to Figs. 1 and 2, the above-mentioned magnetic means for providing restraint on the starter jaw 13 will now be described. A sleeve member 51 is threaded on the extension 37 of the stationary member 35 and is fixed thereon by lock ring 53. The end of ring 53 fits in an axial slot in end of extension 37. The sleeve 51 has four slots 55 in the inner end thereof with inner open ends. Four permanent magnets 57 are positioned in slots 55. Each inner magnet 57 is encased by an insulating cup 59. The inner ends of the magnets have an axially-extending, inwardly-inclined projection 61 which is used to axially confine the magnets. A washer 63 has an annular indentation 65 arranged to receive the projections 61 of the magnets which project out from the slots. A bearing retainer washer 67 extends between positioning ring 63 and the inner race of the bearing 31. The threaded sleeve 51 does not contact positioning washer 63 so that a small gap at the radially-inner location results. With this arrangement, the sleeve 51 axially positions and confines the structure which is inwardly thereof. Magnets 57 have a circumferential length which is equal to a thirty degree arc on the circumference of sleeve 51 and are so constructed that the radially-outer surface of the magnets is the north pole thereof. The axial length of magnets 57 is about twice the length of axial travel of the starter jaw.

The starter jaw 13 has an annular groove 71 in the intermediate part of its internal surface 73. Nine permanent magnets 75 having non-magnetic liners 76 at the bottom and radial-extending sides are uniformly spaced in groove 71 against the inner shoulder thereof. Magnets 75 have radial key-stone sides and are spaced and retained radially by non-magnetic spacers 77 which have complementary radial sides and are positioned between the nine magnets. As shown, the top one of the spacers 77 is positioned as the final step by axially sliding it in

axial slot 78 which is the width of a spacer and extends through an inclined face of a starter jaw tooth 19 to groove 71. It is apparent that, by rearrangement, the bottom surface of the groove could be extended to the outer end of the starter jaw radially inward of the teeth so that the magnets and spacers could be positioned by axially sliding and restrained by a lock ring in a groove. Magnets 75 have the same axial length as magnets 37.

Rotation of the assembly of magnets and spacers relative to the starter jaw is prevented by the key 79 which is slid in keyway 80 in the starter jaw and groove 81 in the top spacer. The assembly of magnets and spacers are restrained axially on the axially-extending surface of the groove 71 by split washer 82 and a resilient split lock ring 83 which abuts the axial outer shoulder of groove 71. The outer magnets 75 have their south poles at the radially-inward face thereof, generally opposite the north poles of magnets 57, and have a circumferential length which is equal to about a thirty degree arc on the circumference of the inner-surface of the starter jaw 13. By reference to Fig. 2, it can be seen that two magnets are in full facing relation and that major portions of the magnets will be in facing relation when there is rotation. The spacers 77 have an arc length of ten degrees. The spacers 77 are made of a cotton-phenol laminate. The non-magnetic cups 59 and liners 76 are made from a phenol-impregnated linen cloth which is about ten thousandths of an inch thick. These non-magnetic parts do not provide a good path for the magnetic flux to the adjacent steel parts. Magnets 57, 75 are made from a high-strength permanent magnetic material such as alnico #5 of the Crucible Steel Co. which consists of 8% aluminum, 14% nickel, 24% cobalt, 3% copper and remainder iron. It is to be noted that the faces of the magnets are closely spaced (.020") and that all magnets project from the mounting structure.

In operation, the starter will be energized and transmit torque to the clutch barrel or drive member 11 which will tend to rotate the starter jaw 13 with it. Axial advancement of the starter jaw 13 for contact with the starter jaw 25 will begin because of the strong magnetic attraction between the magnets 57 and 75 which have full-length opposite poles in substantial facing relation. It is to be noted that, regardless of the slightly variable rotational position of the nine movable magnets 75 relative to the four stationary magnets 57 when the starter is at rest, there will be sufficient magnetic attraction, due to major portions of the magnets being opposed, to impose restraint on the starter jaw so that it easily begins to advance axially by the loosely-fitting helical spline 15, 17. Thereafter, the axial component of the normal force or restraint required for further jaw advancement will continue due to successive facing magnetic attractions during rotation. The completion of jaw engagement will be accomplished by the engine rotor inertial effects. At the time of full jaw tooth engagement, the magnetic attraction will be significantly reduced. The reduced magnetic attraction results because the axial length of the magnets is such that upon full engagement and lateral movement, there is no shearing of strong magnetic flux at about half of the faces of each set of magnets. In this manner, heat generation is reduced under the high-speed cranking conditions. It is to be noted that the geometry of the magnets is such that lateral motion of the starter jaw is impeded but slightly, resulting in rapid advance for small rotation and thereby minimizing engagement shock.

When the engine speed slightly exceeds the starter speed, the forces on the inclined faces of the jaws will cause separation and axial retraction begins. Further retraction of starter jaw over the helical connection, as the drive member is coasting to rest after the starting power is cut off at engine starting speed, will be aided by the magnetic attraction existing after initial axial re-

tracting movement of the starter jaw. After the starter jaw is retracted and is at rest, the magnetic attraction will hold the starter jaw so that it does not move, due to flight maneuvers, to the extent that jaw ratchetting occurs.

It is to be understood that persons skilled in the art can make changes in the embodiment of the invention herein set forth without departing from the invention of the appended claims.

What is claimed is:

1. In a starter having an engine jaw and a starter jaw with the starter jaw being mounted on a drive member by a helical spline connection for axial advancement and retraction, the improvement comprising starter jaw magnetic means on said starter jaw, stationary magnetic means opposed to said starter jaw magnetic means and radially-spaced closely to said starter jaw magnetic means, the facing end of said starter jaw magnetic means being of opposite polarity to the facing end of said stationary magnetic means, said starter jaw magnetic means and said stationary magnetic means being so constructed and arranged that said starter jaw is advanced due to restraint by magnetic attraction between the magnetic means when said drive member is rotated.

2. In a starter having an engine jaw and a starter jaw with the starter jaw being mounted on a drive member by a helical spline connection for axial advancement and retraction, the improvement comprising a plurality of equi-spaced starter jaw magnets mounted in a ring on said starter jaw, a plurality of equi-spaced stationary magnets in a ring opposed to said ring of starter jaw magnets and radially-spaced from said starter jaw magnets, the facing ends of said starter jaw magnets being of opposite polarity to the facing ends of said stationary magnets, said starter jaw magnets and said stationary magnets being so constructed and arranged that said starter jaw is advanced due to restraint by magnetic attraction between the rings of magnets when said drive member is rotated.

3. In a starter having an engine jaw and a starter jaw with the starter jaw being mounted on a drive member by a helical spline connection for axial advancement and retraction, the improvement comprising a plurality of equi-spaced starter jaw magnets mounted in a ring on said starter jaw and projecting therefrom, a plurality of equi-spaced stationary magnets in a ring opposed to said ring of starter jaw magnets and radially-spaced inwardly from said starter jaw magnets, the facing ends of said starter jaw magnets being of opposite polarity to the facing ends of said stationary magnets, said stationary magnets being mounted in stationary member and projecting therefrom, said magnets being of the same axial length so that significantly less magnetic attraction is exerted between the magnets after initial advancement to jaw teeth engagement, whereby said starter jaw is advanced due to restraint by magnetic attraction between the rings of magnets and whereby less shearing of strong magnetic flux occurs after full jaw engagement.

4. In a starter having an engine jaw and a starter jaw with the starter jaw being mounted on a drive member by a helical spline connection for axial advancement and retraction, the improvement comprising a plurality of equi-spaced starter jaw magnets mounted in a ring on said starter jaw and having inner ends of one polarity, a plurality of equi-spaced stationary magnets in a ring radially-spaced inwardly from said starter jaw magnets and having outer ends of polarity opposite to said one polarity, the number of said starter jaw magnets exceeding the number of said stationary magnets so that two magnets of opposite polarity will be in substantially full facing relation when starting from any rest position, the axial dimension of all of said magnets being substantially the same and being about twice the travel distance of said starter jaw so that significantly less magnetic attraction is exerted after initial jaw teeth engagement, whereby said starter jaw is initially advanced due to restraint by

magnetic attraction among the magnets when said drive member is rotated and whereby said starter jaw is held in non-ratchetting position when the starter is not operating.

5. In a starter, the improved starter jaw advancing mechanism comprised of an engine jaw having an axially-extending ring of teeth at one end which face the teeth of the starter jaw and are spaced slightly therefrom, said starter jaw having a helical spline on an intermediate part of its external surface, a drive barrel radially outward of said starter jaw and having an internal helical spline engaging said starter jaw spline for starter jaw advancement into engagement with said engine jaw, said starter jaw having an internal annular surface terminated by an annular shoulder at the intermediate part thereof, an annular assembly of alternated starter jaw magnets and non-magnetic spacers abutting said shoulder, said magnets being shrouded by non-magnetic insulators at the bottom and transverse sides thereof, said magnets and spacers being of keystone transverse cross-section so that they are contained as a ring type structure, means arranged so that one of said spacers is radially-outwardly key-fitted into said internal starter jaw surface to prevent rotation of the assembly relative to the starter jaw, means including a washer and lock ring arranged to axially restrain said assembly, said starter jaw magnets at their radially-inward ends being of the same polarity, a stationary member having bearing means on a shoulder rotatably carrying said drive barrel and having an annular-surfaced extension of less diameter than said shoulder extending from said shoulder to within said starter jaw beyond the location of said assembly, a sleeve threaded on said extension and having a plurality of equi-spaced grooves at the inner end thereof, stationary permanent magnets in said grooves and projecting therefrom and shrouded by non-magnetic cups except for their radially-outer faces, said stationary magnets having their radially-inner faces facing said starter jaw magnets and being closely spaced thereto and of opposite polarity, the axial-width of all of said magnets being about twice the travel distance of said starter jaw, said starter jaw magnets and said stationary magnets being so arranged that there are major portions of facing ends of said magnets in facing relation as said starter jaw is rotated, whereby said magnets exert a restraining force on said starter jaw to cause it to advance when the drive barrel is rotated and to cause it to remain retracted when said drive barrel is stationary and further whereby with full jaw engagement less magnetic flux is sheared adjacent the faces of the magnets.

6. In a starter, the improved starter jaw advancing mechanism comprised of an engine jaw having an axially-extending ring of teeth, a tubular starter jaw having an axial-extending ring of teeth at one end which face the teeth of the engine jaw and are spaced slightly therefrom, said starter jaw having a helical spline on an intermediate part of its external surface, a drive barrel radially outward of said starter jaw and having an internal helical spline

engaging said starter jaw spline for starter jaw advancement into engagement with said engine jaw, said tubular starter jaw having an internal annular surface terminated by an annular shoulder at the intermediate part thereof, an annular assembly of alternated starter jaw magnets and non-magnetic spacers abutting said shoulder, said magnets being shrouded by non-magnetic insulators at the bottom and transverse sides thereof, said magnets and spacers being of keystone transverse cross-section so that they are contained as a ring type structure, means arranged so that one of said spacers is radially-outwardly key-fitted into said internal starter jaw surface to prevent rotation of the assembly relative to the starter jaw, means including a washer and lock ring arranged to axially restrain said assembly, said starter jaw magnets at their radially-inward ends being of the same polarity, a stationary member having bearing means on a shoulder rotatably carrying said drive barrel and having an annular-surfaced extension of less diameter than said shoulder extending from said shoulder to within said starter jaw beyond the location of said assembly, a sleeve threaded on said extension and having a plurality of equi-spaced grooves at the inner end thereof, stationary permanent magnets in said grooves and projecting therefrom and shrouded by non-magnetic cups arranged so that their radially-outer faces, said magnets having inwardly-inclined projections extending axially out from the inner end of said sleeve, a washer on said extension having an annular indentation receiving the radially-inner part of said projections of said stationary magnets and axially restraining said stationary magnets, said stationary magnets having their radially-inner faces facing said starter jaw magnets and being closely spaced thereto and of opposite polarity, the axial-width of all of said magnets being about twice the travel distance of said starter jaw, said starter jaw magnets and said stationary magnets being so arranged that the facing end of one starter jaw magnet faces substantially the entire facing end of one of said stationary magnets when said starter jaw is in retracted position, whereby said magnets exert a restraining force on said starter jaw to cause it to advance when the drive barrel is rotated and to cause it to remain retracted when said drive barrel is stationary, and further whereby with full jaw engagement less magnetic flux is sheared adjacent the faces of the magnets.
